UNITED STATES PATENT OFFICE

167,733

COMBINATION CHEST, WRITING DESK, AND EXTENSION TABLE

Stanley T. Anderson, Jamestown, N. Y., assignor to Alliance Furniture Company, Jamestown,
N. Y., a corporation of New York

Application February 18, 1952, Serial No. 18,575

Term of patent 14 years

(CL. D33—14)

To all whom it may concern:

Be it known that I, Stanley T. Anderson, a citizen of the United States, residing at Jamestown, State of New York, have invented a new, original, and ornamental Design for a Combination Chest, Writing Desk, and Extension Table, of which the following is a specification, reference being had to the accompanying drawing, forming a part hereof.

Fig. 1 is a perspective view of a combination chest, writing desk, and extension table, showing my new design, as it appears when in use as a chest;

Fig. 2 is a perspective view thereof as it appears when in use as a writing desk;

Fig. 3 is a perspective view thereof as it appears in fully extended position as a table with the leaves omitted.

Fig. 4 is a perspective view thereof as it appears in fully extended position as a table with the leaves in place.

The dominant features of this design reside in the portions shown in full lines.

I claim:

The ornamental design for a combination chest, writing desk, and extension table, as shown and described.

STANLEY T. ANDERSON.
